UNITED STATES PATENT OFFICE.

GIOVANNI EMANUELE ELIA, OF NEW YORK, N. Y., ASSIGNOR TO VICKERS LIMITED, OF LONDON, ENGLAND.

SUBMARINE MINE.

1,296,376.

Specification of Letters Patent.

Patented Mar. 4, 1919.

Application filed July 3, 1917. Serial No. 178,367.

To all whom it may concern:

Be it known that I, GIOVANNI E. ELIA, a subject of the King of Italy, residing at New York city, in the county of New York, 5 State of New York, have invented certain new and useful Improvements in Submarine Mines; and I do hereby declare the following to be a full, clear, and exact description of the invention, such as will enable others skilled in the art to which it appertains to 10 make and use the same.

This invention relates to submarine mines of the kind comprising an anchor connected to the flotation chamber or mine 15 proper by a mooring cable the paying out of which is effected by the separation of the flotation chamber and anchor after the mine has been launched and the parts thereof approach or reach the sea bed, means being 20 provided for controlling the paying out of the cable so as to regulate the depth of immersion at which the flotation chamber will be anchored beneath the surface of the water.

25 According to the invention a weight is provided which is normally held attached to the mooring cable and is released at a pre-determined point in the ascent of the flotation chamber, whereupon said weight descends and actuates a device for arresting 30 the unwinding or paying out of the mooring cable. To this end there is provided at a suitable position on the mooring cable a weight slidably mounted on a sleeve or tube 35 attached to the cable and fitted with a hydrostat. The said hydrostat is so constructed and arranged that the water pressure acting on its diaphragm, at any depth below the desired depth of anchoring, retains 40 the weight connected to the cable but when the flotation chamber has ascended to a position at or about the desired depth of anchoring, the reduced water pressure allows the hydrostat to act and free the weight, 45 which thereupon slides down the mooring cable and actuates means which stop the further unwinding or paying out of the cable. Suitable means are provided for preventing the hydrostat from becoming operative 50 until after the flotation chamber has commenced to separate from the anchor.

In order that the said invention may be clearly understood and readily carried into effect the same will now be described more

fully with reference to the accompanying 55 drawings, in which:

Figure 1 illustrates diagrammatically various positions of the mine after being launched and finally coming to anchor with the flotation chamber at a predetermined 60 depth beneath the surface of the water.

Figs. 2, 3 and 4 illustrate diagrammatically on a larger scale how the hydrostatically controlled device is rendered active and the weight released during the ascent of the 65 flotation chamber after the anchor reaches the sea bed.

Fig. 5 is a sectional elevation on a larger scale showing the mine as a whole.

Fig. 6 is a vertical section of the said 70 hydrostatically controlled device shown on a still larger scale.

Fig. 7 is a plan view of Fig. 6 with certain parts removed, and

Fig. 8 is a vertical section (with certain 75 parts omitted) taken approximately on the line X—Y of Fig. 6.

Fig. 9 is a vertical cross section through the anchor at right angles to Fig. 5 showing the drum-winch of the mooring cable and 80 its locking device.

Fig. 10 is an end view of the said locking device in locked position.

A is the mine body or flotation chamber, B is the anchor, and C is the plummet. D 85 is the mooring cable and E is the mooring cable drum. F is a short chain which connects the plummet to the spring controlled locking lever G. H is the hydrostatically controlled device, I is the sliding weight and 90 J is a pivoted lever on the anchor B which lever is actuated by the weight I, when the latter is released by the hydrostatically controlled device H. K is the device for rendering the hydrostatically controlled device 95 H inoperative until after the anchor and the flotation chamber reach the sea bed.

The hydrostatically controlled device H comprises a hollow box-like casing 1 which is firmly attached to the mooring cable in a 100 position contiguous to the flotation chamber A, by a tube 2 which is split at its upper part, a locking plate 3, and bolts 4. 5 is a diaphragm forming part of the hydrostat and having a rod 6 extending through it, the said rod being acted upon at its outer extremity by a helical spring 7, the inner extremity being connected to a pivoted lever 8.

Under the influence of the spring 7 the lever 8 tends to move about its fulcrum 9 but is normally prevented from so doing until the flotation chamber A has ascended from the 5 anchor B, to a position at or about the desired depth of anchoring beneath the surface of the water, by the pressure of the sea water which enters the casing 1 through openings 10 and acts on the side of the dia- 10 phragm opposite to that on which the spring 7 is situated. The sliding weight I is mounted on the lower portion of the tube 2 and is locked against movement by a pivoted lever 11 one end of which engages beneath a 15 chamfered flange 12 on the weight I, and the other end of which engages a shoulder or recess 13 at the upper end of the lever 8. 14 is a helical spring which bears upon the upper end of the lever 8, the tension of which can 20 be adjusted as desired so as to vary the moment of release of the lever 8 by means of a regulated device 15 provided with an index 25 16. The lever 8 is locked against movement until the flotation chamber and the anchor 30 reach the sea bed by the aforesaid device K which comprises a locking bolt 19 which engages the lower extremity of the lever 8 and is normally locked to the casing 1 by a shearable pin 20. Connected to the bolt 19 is a 35 short cord 21 which is attached to the anchor B at the point 22. The lever J is hingedly connected at 23 to the top plate of the anchor and carries a part 24 which normally bears upon or lies immediately above a shoulder 40 25 on an arm 26 which is pivoted at 26' on the anchor and is normally held out of engagement with the toothed rim 27 of the mooring cable drum by a spring detent 28, comprising a pin which is normally held in 45 locking engagement with an opening in the plate 28' by spring pressure.

During the descent of the mine to the sea bed, the plummet C holds the lever G in engagement with the toothed rim 27 of the 50 cable drum against the influence of the spring 29. Immediately the plummet reaches the sea bed its weight is removed from the lever C and the spring 29 disengages the said lever C and releases the winch 55 drum E (Figs. 2, 3 and 4). Owing to its buoyancy the flotation chamber A then separates from the anchor and the mooring cable D is paid out, preferably under the control of a hydraulic brake (not shown). The tension placed on the cord 21 thereafter shears the pin 20 and withdraws the bolt 19 thus liberating the lever 8 and releasing the hydrostatically controlled device. When the flotation chamber has ascended to a position 60 at or about the desired depth beneath the surface of the water the reduced water pressure on the diaphragm 5 allows the spring 7 to move the rod 6 inward, thus rocking the lever 8 about its fulcrum 9 and disengaging 65 the same from the lever 11, which then no-

longer acts to support the weight I so that the latter is released and slides down the mooring cable by the action of gravity until it is arrested by striking the lever J (see Fig. 4). The shock of impact displaces 70 the spring detent 28 which supports the arm 26 from the opening in the plate 28', and forces the free end of the arm 26 into engagement with the toothed rim 27 of the mooring cable drum, thus stopping the fur- 75 ther paying out of the mooring cable and the flotation chamber A remains anchored at the desired depth. The strength of the spring 7 which acts on the diaphragm 5 will determine the point in the ascent of the flotation 80 chamber at which the weight will be released; and the moment of release may be further regulated for instance by the device 15 so as to effect the release at any predetermined depth to which the flotation chamber 85 is required to be anchored beneath the surface of the water.

What I claim and desire to secure by Letters Patent of the United States is:—

1. A submarine mine comprising a flotation chamber or mine proper, an anchor, a mooring cable, connecting said flotation chamber and said anchor, paying out gear for said mooring cable, means for releasing the flotation chamber from the anchor after the mine has been launched and the parts thereof approach or reach the sea bed, a weight normally held attached to the mooring cable, means for releasing said weight at a predetermined point in the ascent of the flotation chamber, and means actuated by said weight for arresting the continued unwinding or paying out of the mooring cable. 90

2. A submarine mine comprising a flotation chamber or mine proper, an anchor, a mooring cable connecting said flotation chamber and said anchor, paying out gear for said mooring cable, means for releasing the flotation chamber from the anchor after the mine has been launched and the parts thereof approach or reach the sea bed, a weight normally held attached to the mooring cable, a hydrostatically controlled device for releasing said weight at a predetermined point in the separation of the flotation chamber and anchor, and means actuated by said weight for arresting the unwinding or continued paying out of the mooring cable. 100

3. A submarine mine comprising a flotation chamber or mine proper, an anchor, a mooring cable connecting said flotation chamber and said anchor, paying out gear for said mooring cable, means for releasing the flotation chamber from the anchor after the mine has been launched and the parts thereof approach or reach the sea bed, a weight normally held attached to the mooring cable, a hydrostatically controlled de- 110 115 120 125 130

vice for releasing said weight at a predetermined point in the separation of the flotation chamber and anchor, means actuated by said weight for arresting the unwinding or continued paying out of the mooring cable, and means for rendering the hydrostatically controlled device inoperative until after the flotation chamber has commenced to separate from the anchor.

10 4. A submarine mine comprising a flotation chamber or mine proper, an anchor, a mooring cable connecting said flotation chamber and said anchor, paying out gear for said mooring cable, means for releasing the flotation chamber from the anchor after the mine has been launched and the parts thereof approach or reach the sea bed, a weight normally held attached to the mooring cable, a hydrostatically controlled device 15 for releasing said weight at a predetermined point in the separation of the flotation chamber and anchor, means actuated by said weight for arresting the unwinding or continued paying out of the mooring cable, 20 means for rendering the hydrostatically controlled device inoperative until after the flotation chamber has commenced to separate from the anchor, and means for enabling the hydrostatically controlled device 25 to be initially set to release the weight at any predetermined depth.

5. A submarine mine comprising a flotation chamber or mine proper, an anchor, a mooring cable connecting said flotation chamber and said anchor, paying out gear for said mooring cable, means for releasing the flotation chamber from the anchor after the mine has been launched and the parts thereof approach or reach the sea bed, a weight normally held attached to the mooring cable, a hydrostatically controlled device for releasing said weight at a predetermined point in the separation of the flotation chamber and anchor, said hydrostatically controlled device comprising a flexible spring controlled diaphragm and two pivoted levers, one of said levers retaining the weight in a fixed position on the mooring cable and the other of said levers acting to 40 lock the weight retaining lever against movement until the said diaphragm is displaced by its spring overcoming the pressure of the water when the flotation chamber in its ascent arrives at or near the predetermined 45 depth at which it is to be anchored below the surface and means actuated by said weight for arresting the unwinding or continued paying out of the mooring cable.

6. A submarine mine comprising a flotation chamber or mine proper, an anchor, a mooring cable connecting said flotation chamber and anchor, paying out gear for said mooring cable, means for releasing the flotation chamber from the anchor after the mine has been launched and the parts thereof

approach or reach the sea bed, a weight normally held attached to the mooring cable, a hydrostatically controlled device for releasing said weight at a predetermined point in the separation of the flotation chamber and anchor, said hydrostatically controlled device comprising a flexible spring controlled diaphragm and two pivoted levers, one of said levers retaining the weight in a fixed position on the mooring cable and the other of said levers acting to lock the weight retaining lever against movement until the said diaphragm is displaced by its spring overcoming the pressure of the water when the flotation chamber in its ascent arrives at or near the predetermined depth at which it is to be anchored below the surface, a spring controlled regulating device co-operating with one of said levers for determining the moment when the hydrostatically controlled device will act and said weight will be released, and means actuated by said weight for arresting the unwinding or continued paying out of the mooring cable.

7. A submarine mine comprising a flotation chamber or mine proper, an anchor, a mooring cable connecting said flotation chamber and said anchor, paying out gear for said mooring cable, means for releasing the flotation chamber from the anchor after the mine has been launched and the parts thereof approach or reach the sea bed, a weight normally held attached to the mooring cable, a hydrostatically controlled device for releasing said weight at a predetermined point in the separation of the flotation chamber and anchor, said hydrostatically controlled device comprising a flexible spring controlled diaphragm and two pivoted levers, one of said levers retaining the weight in a fixed position on the mooring cable and the other of said levers acting to lock the weight retaining lever against movement until the said diaphragm is displaced by its spring overcoming the pressure of the water when the flotation chamber in its ascent arrives at or near the predetermined depth at which it is to be anchored below the surface, a spring controlled regulating device co-operating with one of said levers for determining the moment when the hydrostatically controlled device will act and said weight will be released, a locking device which holds said hydrostatically controlled device in an inoperative position, said locking device being caused to release the hydrostatically controlled device when the flotation chamber separates from the anchor after the parts of the mine reach the sea bed, and means actuated by said weight for arresting the unwinding or continued paying out of the mooring cable.

8. A submarine mine comprising a flotation chamber, or mine proper, an anchor, a mooring cable connecting said flotation

- chamber and said anchor, paying out gear for said mooring cable, means for releasing the flotation chamber from the anchor after the mine has been launched and the parts thereof approach or reach the sea bed, a weight normally held attached to the mooring cable, and a pivoted arm in the anchor which is normally held out of engagement with the paying out gear for the mooring cable until released by the impact of the falling weight whereupon it engages with said paying out gear and arrests the further unwinding or paying out of the mooring cable.
9. A submarine mine comprising a flotation chamber or mine proper; an anchor, a mooring cable connecting said flotation chamber and said anchor, paying out gear for said mooring cable, means for releasing

the flotation chamber from the anchor after the mine has been launched and the parts thereof approach or reach the sea bed, a weight normally held attached to the mooring cable, a hydrostatically controlled device for releasing said weight at a predetermined point in the separation of the flotation chamber and anchor, and a pivoted arm in the anchor which is normally held out of engagement with the paying out gear for the mooring cable until released by the impact of the falling weight whereupon it engages with said paying out gear and arrests the further unwinding or paying out of the mooring cable.

In testimony whereof I affix my signature.

GIOVANNI EMANUELE ELIA.
